WRAPPER FEEDING AND CUTTING DEVICE

Donald M. Hunter, Spokane, Wash.

Original application August 28, 1934, Serial No. 741,769. Divided and this application January 13, 1936, Serial No. 58,921

12 Claims. (Cl. 164—49)

The present invention relates to a wrapper feeding and cutting device and is particularly directed to improvements in the means for sizing the wrappers and positioning them relative to the wrapping mechanism.

This application is a division of my application Serial No. 741,769 filed August 28, 1934 for Fruit wrapping machines and presents certain new and useful improvements for varying the size of the wrapper according to the size of the object to be wrapped and includes means for centering the wrapper relative to the wrapping mechanism, as is essentially necessary to proper wrapping.

The wrappers are fed from a continuous web, preferably in the form of a roll and passed between rollers which are periodically turned by an auxiliary mechanism fractionally turned. The fractional movements of the auxiliary mechanism are controlled by means of a rotatable disc eccentric thereof and this disc is provided with an eccentric pivot carrying a connecting rod by means of which the auxiliary mechanism is made to turn the rollers. By rotating the disc, the excursions of the rollers are varied while the stroke of the connecting rod remains constant.

Means are provided to interrupt the delivery of the wrappers when required for any reason, such as the temporary absence of objects to be wrapped, or for the purpose of installing a new roll of wrappers.

Means are provided to slidably adjust the wrapper cutting mechanism to and from the wrapping means, to thereby center each size of wrapper relative to the wrapping station.

The accompanying drawings illustrate the form in which I have reduced my invention to practice and it will be understood that modifications may be made in the disclosed construction without departing from the principles of the invention and the intent of the claims.

Figure 1 shows the invention and a fragment of a wrapping machine.

Figure 2 is an enlarged detail view of the wrapper feeding and sizing mechanism.

Figure 3 is an enlarged sectional view of the wrapper sizing mechanism.

Figure 4 is a vertical section of Figure 2.

Figure 5 is a vertical section of Figure 1.

Figure 6 is an underside view disclosing the sliding adjustment.

The device may be individually operated and employed to deliver sized sheets in stacked formation, or it may be installed in various forms of wrapping machines and operated from their

drive means in coordination with the wrapping operation.

In Fig. 1 the invention is shown housed in the frame N which is slidably mounted on the frame F of a wrapping machine having a wrapping station A which may take any suitable form and the wrapping operation may be accomplished in any suitable manner, such details being no part of the present invention.

The frame N may consist of any suitable end-plates supported upon a base. The roller 12 is journaled in the frame N and the roller 13 is journaled in a floating bearing vertically slidable in the frame. The spring 13a urges the roller 13 towards the roller 12 which is provided with a pinion 11 which is turned by means of a gear 10.

As seen in Figure 4, the gear 10 and the drum 9 are both journaled on a dead spindle rigid with the frame N and bearing surface is enhanced by an internal hub on the drum 9. As seen in Figures 2 and 4, a ratchet wheel 10a is rigid with the gear 10, and the drum 9 carries a pawl 9a adapted to engage the ratchet wheel 10a. This pawl is urged by a suitable spring carried by the drum 9 which also carries the detent 9c which is adapted to hold the pawl free of the ratchet wheel when required for any reason.

The disc 9e is rotatably mounted on the exterior of the drum 9 and eccentrically thereof. The connecting bar 8 is pivoted eccentrically of the disc 9e, whereby rotation of the disc 9e will alter the radial distance between the axis of the drum 9 and the pivot of the bar 8, which of course affects the rotation of the drum 9, the thrust of the bar 8 being constant. The disc 9e may be held in any required position of rotation by any suitable means, as for instance by means of the post 9f engaging one of a series of spaced notches on the periphery of the disc 9e. The disc 9e may be recessed into an appropriate boss 9h, in which case the boss is of course bored to admit the post 9f, which latter member is preferably threaded into the drum 9. Three appropriately positioned posts similar to 9f may be utilized and the disc 9e rotated in its boss, pivoting of said disc being omitted. The present means is used for the convenience of illustration, and for greater facility, I employ a spring pressed detent pin, appropriately located in the pivoted disc 9e and alternately engaging in complementary holes, spaced in a semicircular arrangement in the drum 9 and concentric with the pivoted disc 9e.

A suitable scale designating the size of the wrappers is illustrated in Figure 2 and an appro-

priate mark on the disc 9e indicates the adjusted size. It should be mentioned that the decentration of the pivot for the bar 8 is exaggerated for the convenience of illustration, and that relatively less eccentric position is required.

The disc 9e may be manually rotated, or suitable mechanical means may be employed, as for instance the disc may be provided with teeth adapted to be turned by a worm.

From the foregoing description it will be readily understood that the pivotal connection of the connecting bar 8 can be varied between the two extremes indicated by the arrows in Figure 2 and that the resulting difference in distance from the axis of the drum 9 will alter the excursions of the rollers 12 and 13 and consequently the length of wrapper delivered thereby.

The illustrated drum 9 is preferable for commercial practicability; but of course, this drum 20 may be supplanted by a radius arm carrying the instrumentalities otherwise carried by the drum. It will also be understood that the ratchet mechanism may be supplanted by a suitable clutch mechanism, as for instance the invention was 25 originally reduced to practice with a roller clutch carried by the drum 9 and engaging complementary parts carried by the gear 10.

The wrappers are provided in a roll E supported on a spindle 16 detachably mounted in the 30 open slots 16a provided in a vertical extension of the frame N, and a suitable spring 16b prevents excess rotation of the wrapper roll E. From this roll, the wrappers are fed between the rollers 12 and 13 and passed between the knives 14 and 35 14a, as indicated by the dot and dash line in Figure 5. The knife 14 is rigid with the frame N and the ends of the knife bar 14a are vertically slidably in the guides 14b fashioned in the frame N. The knife bar 14d is formed with a lip which extends within close proximity to the roller 12 40 and forms an apron bridging the gap between this roller and the knife 14, thus adequately supporting the wrapper in required position for cutting.

The knife 14a and the connecting bar 8 may be 45 operated by any convenient means and coordinated with the wrapping mechanism as occasion requires. In the present instance, I have shown the frame N carrying the wrapper roll and the previously described mechanism, slidably mounted 50 as a unit on the frame F of a wrapping machine having a wrapping station A. On opposite ends of the shaft M are cams 3 and 4 rigid with the shaft which turns counterclockwise in Figures 1 and 5. As seen in Figure 1, to the cam 4 55 is secured an arm 4a, to which is pivoted the connecting bar 5, the opposite end of this bar is pivoted to the rocker arm 6a on the collar 6 which turns fractionally on the dead spindle 7 secured in the frame F, the collar 6 being retained 60 upon this spindle by a suitable collar 7a. The collar 6 carries a second rocker arm 6b to which the connecting bar 8 is pivoted.

The knife bar 14a is connected to the lever 15, by means of the link 15a and like structure is 65 provided on each end of the knife bar 14a. The levers 15 are in the nature of bell cranks and are each fulcrumed as indicated at 15b and are pendant therefrom, their lower ends engaging with the aforementioned cams 3 and 4, by which 70 they are actuated once upon each revolution of the shaft M. As seen in Figure 1, the cams engage the levers after the radius arm 4a has completed its full stroke, and from this description, it will be seen that the rollers 12 and 13 complete 75 their excursion, remain stationary, after which

the knife 14a is actuated. As shown in Figure 5, the cam 3 is set slightly in advance of the cam 4 to afford the proper shear action, and of course the necessary freedom is provided in the pins 14c. The shaft M and the cams 3 and 4 are 5 here shown as a part of the wrapping machine to which the invention is attached and it will be readily understood that this shaft and its cams may be mounted immediately above the knife bar 14a so as to urge it downward against suitable 10 springs; in which case, the connecting bar 8 can be pivoted direct to the arm 4a, thereby eliminating the intermediate parts illustrated in Figure 1, and also eliminating the levers 15 and links 15a; and of course the shaft can be turned in any 15 suitable manner.

The sizing of the wrappers is supplemented by appropriate width of the wrapper roll E and each size of wrapper is properly positioned relative to the wrapping station A by slidably adjusting the 20 frame N to and from the wrapping station. The slidable adjustment of the frame N may be accomplished in any practical manner, as for instance by means of bolts, each slidable in a slot in the base of the frame N and threaded into 25 the cross member I, as shown in Figure 5. Preferably, the cross member I and the base of the frame N are spaced by appropriate bosses each having a suitable key-way to assure constant alignment. As seen in Figure 6, the lever 18, 30 which is in the nature of a bell crank, is fulcrumed on a pivot 21 in the cross member I and provided with a stud 19 engaging in a slot 20 in the base of the frame N, whereby the lever 18 can be employed to slidably adjust the frame N as 35 required, a suitable scale and indicator being provided on the exterior as illustrated in Figure 1; and for practical purposes, this scale is preferably, separate and applied in any convenient manner.

As seen in Figure 5, the gap between the knife 40 14 and the wrapping station A is bridged by the apron 17 which is attached to frame N and supported by the table of the wrapping machine. The apron 17 is of appropriate size to prevent it 45 from leaving the wrapping table when the frame N is retracted to the maximum and also to prevent it from encroaching unduly upon the wrapping station when the frame N is advanced to its most forward position.

To accommodate instances where the supply of articles to be wrapped is momentarily interrupted, it is advantageous to interrupt the delivery of wrappers without stopping the machine. This 50 may be accomplished by a suitable detent engaging the ratchet pawl 9a, whereby the latter member is held free of the ratchet wheel 10a. Preferably, I employ a small cam 9c pivoted in the drum 9 and externally thereof provided with a hand wheel or thumb-key 9d, the operation of 55 which will appear obvious, the action being illustrated in Figure 4. Other means may be employed for interrupting the delivery of the wrappers, as for instance the pinion 11 may be feathered on its shaft and the former provided 60 with an appropriate hand wheel, preferably free upon a collar rigid with said pinion, whereby said pinion may with facility be disengaged and reengaged with the gear 10; or, the pinion 11 may be free upon its shaft and held in position 65 by a collar rigid with said shaft, said collar having a secondary transverse bore through which passes a detent pin, which latter member engages in a complementary transverse bore in the pinion 11. The detent pin may be moved by any suitable 70 75 80 85 90 95

means, as for instance, by a slidable collar, preferably provided with a handwheel, free thereupon, and obviously said retaining collar being rigid with its shaft, the pinion 11 will turn the 5 shaft when engaged with said rigid collar by means of the described detent pin and disengagement will permit the pinion 11 to turn free upon its shaft unaccompanied by rotation of the rollers 12 and 13. Either of such provisions will pre-10 clude the necessity of stopping the machine to preclude the delivery of wrappers in the absence of objects to be wrapped, which is of course objectionable.

In the operation of the invention, the wrappers 15 are fed from roll E, and passed between the rollers 12 and 13, the disc 9e is then rotated to required position and secured by means of the post 9f, the frame N is slidably adjusted to center the wrapper relative to the wrapping station A. 20 From the relative position of the parts as illustrated, it will be obvious that as the cams turn counterclockwise they will contact the levers 15 and sever the stationary wrapper, the first half turn constituting the idle stroke of the wrapper 25 feeding mechanism and the second half turn actuating the rollers 12 and 13 to deliver the sized wrapper; the rollers then remain stationary and as the cams continue to turn, the delivered wrapper will be severed. It will be readily understood 30 that the size of the wrapper can be varied by rotating the disc 9e and that each size of wrapper can be properly centered relative to the wrapping station A by slidably adjusting the frame N. When required for any reason, the 35 delivery of the wrappers can be interrupted by means of the thumb-key 9d, without the necessity of stopping the entire mechanism.

In the invention herein disclosed, what I claim as new and desire to secure by Letters Patent of 40 the United States is:

1. A feeding and cutting device comprising a pair of feed rollers, a wheel operatively connected with one of said rollers, a crank pin carrying member journaled coaxially of said wheel, 45 rotatable means for moving said crank pin to alter its radial distance from said coaxial center, a connecting bar pivoted on said crank pin, means for reciprocating said connecting bar, means for periodically interengaging said coaxial members to produce rotation of said rollers, a cutting 50 device coordinated with said feed rollers, and means for actuating said cutting device during each quiescent period of said rollers.

2. A feeding and cutting device comprising a 55 pair of feed rollers, a wheel operatively connected with one of said rollers, a crank pin carrying member journaled coaxially of said wheel, rotatable means for moving said crank pin to alter its radial distance from said coaxial center, a 60 connecting bar pivoted on said crank pin, means for reciprocating said connecting bar, means for periodically interengaging said coaxial members to produce rotation of said rollers, manually operated means for engaging and disengaging the 65 mechanism from operative relation with said rollers, a cutting device coordinated with said feed rollers, and means for actuating said cutting device during each quiescent period of said rollers.

70 3. A feeding and cutting device comprising a pair of feed rollers, a wheel adapted to turn one of said rollers, means pivoted coaxially of said wheel and carrying a reciprocating drive means eccentrically movable about a pivot eccentric of 75 said coaxial center, means for holding said drive

means at a predetermined radial distance from said coaxial center, means for reciprocating said drive means, means for interengaging said coaxial members to produce periodic fractional movements of said wheel in one direction, a pair 5 of coacting knives, and means for actuating said knives while said rollers are stationary.

4. A feeding and cutting device comprising a pair of feed rollers, a wheel adapted to turn said rollers, means for periodically turning said wheel 10 fractionally, said means coaxially pivoted with said wheel and carrying a rotatable member having a connecting bar pivoted eccentrically thereof, means for locking said rotatable member, means for reciprocating said connecting bar, a 15 cutting device, and means for actuating said cutting device while said rollers are stationary.

5. A feeding and cutting device comprising a pair of feed rollers, a wheel adapted to turn one 20 of said rollers, a member rotatably mounted coaxially with said wheel, a plate pivoted eccentrically of said rotatable member, reciprocating drive means pivoted eccentrically of said plate, means for holding said plate in fixed relation to said rotatable member, means for reciprocating 25 said drive means, means for interengaging said wheel and rotatable member during one direction of rotation, a pair of coacting knives correlated with said feed rollers and means for actuating said knives after each excursion of said 30 feed rollers.

6. A feeding and cutting device comprising a pair of feed rollers, pivoted means for actuating said rollers, a rotatable disc carried by said actuating means and eccentrically thereof, a connecting bar pivoted eccentrically of said disc, means for locking said rotatable disc, means for actuating said connecting bar, a pair of coacting knives correlated with said feed rollers and means for actuating said knives while the feed 40 rollers are stationary.

7. A feeding and cutting device comprising a pair of feed rollers, a ratchet wheel operatively connected with one of said rollers, a pawl carrying member mounted coaxially of said ratchet wheel, a crank pin carrying member radially spaced and rotatably mounted upon said pawl carrying member, means for holding said crank pin carrying member in selective position of relative rotation to radially space its crank pin from the axis of said pawl carrying member, a connecting bar pivoted on said crank pin, means for reciprocating said connecting bar to produce periodic rotation of said rollers, a cutting device 50 coordinated with said feed rollers, and means for actuating said cutting device during each quiescent period of said rollers.

8. A feeding and cutting device comprising a pair of feed rollers, a ratchet wheel operatively connected with one of said rollers, a pawl carrying member mounted coaxially of said ratchet wheel, a crank pin carrying member radially spaced and rotatably mounted upon said pawl carrying member, means for holding said crank pin carrying member in selective position of relative rotation to radially space its crank pin from the axis of said pawl carrying member, a connecting bar pivoted on said crank pin, means for reciprocating said connecting bar to produce 60 periodic rotation of said rollers, manually operated means for engaging and disengaging the mechanism from operative relation with said rollers, a cutting device coordinated with said feed rollers, and means for actuating said cutting 65 device during each quiescent period of said rollers.

ting device during each quiescent period of said rollers.

9. A feeding and cutting device comprising a frame slidably mounted on a support, a cutting device carried by said frame, a pair of feed rollers, means for periodically actuating said feed rollers, means eccentrically rotatable about an eccentric pivot and adapted to alter the excursions of said rollers, means for periodically actuating said cutting device while said feed rollers are stationary, and means for slidably adjusting said frame.

10. A feeding and cutting device comprising a frame slidably mounted on a support, feed rollers carried by said frame, a knife bar rigid with said frame, a knife carried by said knife bar, said knife bar formed with a lip bridging the gap between said knife and one of said rollers, an apron carried by said frame and correlated with said knife, a movable knife correlated with said rigid knife, means for periodically actuating said feed rollers, means eccentrically rotatable about an eccentric pivot and adapted to alter the excursions of said rollers, means for periodically actuating said movable knife while said feed rollers are stationary, and means for slidably adjusting said frame.

11. A feeding and cutting device comprising a slidably mounted frame, a knife carried by said

frame, a pair of feed rollers, a pinion adapted to turn one of said rollers, a gear engaged with said pinion, a ratchet wheel rigid with said gear, a rotatable drum, said gear and drum coaxially mounted, a pawl carried by said drum and engaging said ratchet, a disc rotatably mounted upon said drum and eccentric thereof, a connecting bar pivoted eccentrically of said disc, means for holding said disc in fixed relation with said drum, means for reciprocating said connecting bar, and means to actuate said knife.

12. A feeding and cutting device comprising a slidably mounted frame, a pair of feed rollers, a pinion adapted to turn one of said rollers, a gear engaged with said pinion, a ratchet wheel rigid with said gear, a rotatable drum, said gear and drum coaxially mounted, a pawl carried by said drum and engaging said ratchet, a disc rotatably mounted upon said drum and eccentric thereof, a connecting bar pivoted eccentrically of said disc, means for holding said disc in fixed relation with said drum, means for reciprocating said connecting bar, a fixed knife bar having a lip extending in proximity to one of said rollers, a knife rigid with said knife bar, an apron correlated with said knife, a movable knife coacting with said rigid knife, and means to actuate said movable knife.

DONALD M. HUNTER.
